By *John W. Connerell, Atty.*

UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

SUPPORTING-SPRING MOUNTING.

1,249,321.

Specification of Letters Patent. Patented Dec. 11, 1917.

Application filed August 3, 1917. Serial No. 124,666.

To all whom it may concern:

Be it known that I, EDWIN G. BUSSE, a citizen of the United States, residing at Chicago, Illinois, have invented a certain new and useful Improvement in Supporting-Spring Mountings, of which the following is a full, clear, and exact description, such as will enable others skilled in the art to which it appertains to make and use the same, reference being had to the accompanying drawings, forming part of this specification.

10 This invention relates to railway truck equipment, and particularly to an improved arrangement for mounting the conventional third and fourth point supporting springs, which are commonly used in association with brake rigging to provide a forward guide and a safety support for the brake beams.

15 The object of the present improvement is to provide an arrangement for mounting the supporting springs on the spring plank in such fashion that they may be properly and securely maintained in operative position, and yet may be quickly and easily removed, when desired, to facilitate unhanging of the brake beam or making other repairs to associated truck portions.

20 As is well known in present practice, it frequently occurs, when repairs are being made upon the brake beam or other truck portions, that the third or fourth point supporting springs, if permanently affixed to the spring plank, are bent down to an inoperative position by the workmen, and then are not restored to operative position; or, if they are removably mounted, frequently are not replaced after repairs are made. By 25 means of the present improvement, I provide a form of mounting in which the removal and the replacement of the supporting springs are so easily accomplished that no temptation is offered a workman to avoid 30 those operations. The arrangement is designed particularly for those forms of spring plank and supporting springs in which the latter are shaped for the accommodation of the spring plank or parts thereof so that the 35 supporting springs cannot be removed by longitudinal movement or by rotary move-

ment, but may be removed by bodily movement longitudinally of the spring plank.

In the accompanying drawings, the various forms in which the invention may be embodied are shown, Figure 1 being a partial side elevation of a third or fourth point supporting spring shown in association with the spring plank, the latter being shown in section and equipped with one form of my improved attaching arrangement.

Fig. 2 is a top plan view of a portion of the same construction.

Fig. 3 is a sectional view taken longitudinally of the spring plank substantially on the line 3—3 of Fig. 2.

Fig. 4 is a detail in the nature of a partial top or plan view of another form.

Fig. 5 is a sectional elevation such as would be seen substantially on the line 5—5 of Fig. 4, and

Fig. 6 is a similar sectional elevation of a third form.

In each of the several illustrations, the corresponding parts are indicated by similar reference numerals, the numeral 1 designating the spring plank which is of conventional channel form, and upon which the third or fourth point supporting spring 2 is carried. The spring is bent to accommodate the lateral flanges of the spring plank, and so as to make contact with the upper surface of the plank intermediate the lateral flanges. The extremities of the spring extend outwardly from opposite sides of the spring plank in the usual fashion for the customary association with the brake beams. Mounted on the upper side of the spring plank are bracket members 4, each having a portion 4^a spaced away from the upper surface of the spring plank for the reception and accommodation of the supporting spring 2, and having its outer extremity shaped to facilitate the insertion of the supporting spring thereunder. The bracket 4 forms a stop which limits the movement of the spring in one direction longitudinally of the spring plank. Mounted on the spring plank in association with the bracket 4 is a flexible or elastic retaining member 5, shaped with a portion 5^a which is adapted to engage the spring 2 under the normal tendency of the

- retaining member. This retaining member may be mounted above the bracket and have coöperation with the spring 2 through an aperture in the bracket, as illustrated in Figs. 1, 2 and 3, or it may be mounted on the spring plank and have coöperation with the bracket 4 through an aperture in the spring plank as shown in Fig. 6. If desired, the spring 2 may be provided with a notch for the accommodation of the portion 5^a, and the spring plank may be provided with an aperture for the accommodation of the portion 5^a, as illustrated in Figs. 4 and 5. The essential disposal of the bracket 4 and retaining member 5 must be such that the latter will prevent withdrawal of the spring through the normal open side of the former, no matter in what relationship the two are disposed.
- 20 By virtue of this construction, whenever it is desired to insert or remove the spring 2, the retaining member 5 is retracted so as to clear the open side of the bracket to permit the passage of the spring. When the spring 25 is seated within the bracket, it is held against movement in one direction longitudinally of the spring plank by the bracket itself, and in the other direction by the removable retaining member 5. The engagement 30 of the portion 5^a with the notched portion of the spring also operates to hold the latter against movement transversely of the spring plank. The forming of the spring for engagement with the lateral flanges of 35 the spring plank coöperates with this form of mounting to prevent rotary movement of the spring on the plank, and the provision of a plurality of the brackets 4 and retaining members 5 likewise operates to prevent rotary movement of the spring.
- With this arrangement, the stresses to which the supporting spring is subjected are transmitted to the spring plank itself, as the direction of said movements is downward. 45 Thus the brackets 4 and retaining members 5 are relieved of the actual supporting function, and operate practically as retaining members to hold the springs in proper position on the plank.
- 50 This form of mounting has various other advantageous features. All of the parts are retained permanently on the spring plank, it not being necessary to loosen any bolts or detach any portions in order to free the 55 spring. Only a minimum extent of movement of the spring is required in order to free it entirely from the attaching means, said extent of movement being simply that of the width of the spring. The movement 60 of the spring in the process of detaching it is such as to free it from contact with the third point supporting chairs so that, as soon as the spring has been moved laterally sufficiently to free it from the brackets 4, it 65 is also freed of the weight of the brake

beams, and may be readily lifted from the spring plank.

Various other advantages of this construction will occur to those skilled in the art, as will also various other forms in which the invention herein illustrated and described may be incorporated, and while the foregoing is a description of the forms which I now believe to be the best, it is not my intention that the appended claims be limited thereto, but that they comprehend all other modifications embodying the invention.

What I claim is:

1. In a truck, the combination of a spring plank, a bracket mounted on top of the same, said bracket having a portion directed toward one extremity of the spring plank and spaced apart from the spring plank and a portion directed toward the opposite extremity of the spring plank and forming a stop or seat, and a movable retaining member permanently mounted on the spring plank and adapted to form a closure between the first mentioned portion of the bracket and an associated portion of the spring plank.
2. In a truck, the combination of a spring plank, a bracket mounted on top of the spring plank and shaped to accommodate a third or fourth point supporting spring, the said bracket having a portion directed toward one extremity of the spring plank and spaced apart from the spring plank to permit the insertion of a third or fourth point supporting spring and a portion directed toward the opposite extremity of the spring plank and adapted to coöperate with the spring to limit its movement in that direction, and a movable retaining member permanently mounted on the spring plank and adapted when in operative position to prevent removal of the spring from the bracket.
3. In a truck, the combination of a spring plank, a bracket mounted on top of the spring plank, said bracket having a portion shaped to accommodate a third or fourth point supporting spring between it and the spring plank, said portion being disposed to prevent movement of the accommodated spring upwardly from the spring plank, said bracket having another portion adapted to limit the movement of the accommodated spring longitudinally of the spring plank in one direction, and a movable retaining member mounted on the spring plank and adapted to limit the movement of the accommodated spring in the other direction longitudinally of the spring plank.
4. In a truck, the combination of a spring plank, a bracket mounted on top of the spring plank and having a portion adapted to accommodate a third or fourth point supporting spring and maintain it in contact with the upper surface of the spring plank,

said portion of the bracket being shaped to permit the insertion and removal of the spring by movement longitudinally of the spring plank, and a movable retaining member operably associated with the bracket and effective when in normal position to prevent removal of the spring therefrom.

In testimony whereof I hereunto affix my signature in the presence of two witnesses, this 3rd day of August, 1917.

EDWIN G. BUSSE.
